(57) **CLAIM**

The ornamental design for a smart interactive display board, as shown and described.

DESCRIPTION

FIG. 1 is a front view of a smart interactive display board; FIG. 2 is a rear view thereof; FIG. 3 is a left side view thereof; FIG. 4 is a right side view thereof; FIG. 5 is a top view thereof; FIG. 6 is a bottom view thereof; FIG. 7 is a bottom rear perspective view thereof; FIG. 8 is an enlarged detail view of FIG. 3; FIG. 9 is an enlarged detail view of FIG. 4; FIG. 10 is an enlarged detail view of FIG. 6; and, FIG. 11 is an enlarged detail view of FIG. 7.

The even-dash broken lines in the drawings show portions of the smart interactive display board and form no part of the claimed design. The dash-dot broken lines, encircling portions of the design in FIGS. 3-4, and 6-11 indicate the bounds of the detail views and form no part thereof.

1 Claim, 11 Drawing Sheets
